UNITED STATES PATENT OFFICE.

CHARLES R. CONABEE, OF BUTLER, PENNSYLVANIA.

EXTENSION-LADDER LOCK.

1,113,413.

Specification of Letters Patent.

Patented Oct. 13, 1914.

Application filed January 6, 1914. Serial No. 810,595.

To all whom it may concern:

Be it known that I, CHARLES R. CONABEE, a citizen of the United States of America, and resident of Butler, Pennsylvania, have 5 invented a new and useful Improvement in Extension-Ladder Locks, which invention is fully set forth in the following specification.

The present invention relates to extension ladders, and particularly is an improvement in the devices employed to secure together the two sections of the ladder. These devices are usually attached to the upper or movable section and are provided with pivoted hooks that engage the rungs of the lower section.

The objects of the invention are to provide a compact, simple, strong, economical, positive-acting device of the character indicated, 20 the parts of which may be readily assembled, disassembled, put in position on the ladder sections and removed therefrom.

One of the principal features of the invention is that the pivoted hook that engages the rungs of the lower section is mounted upon the side guard or guide which is carried by the upper section, the parts being secured in position by means passing through the side guard and hook. This 30 makes a device of great strength, simplicity and compactness. Preferably, a casing or cover is associated with the parts, said cover being mounted on the means that pass through the side guard and hook. Further, 35 positive action of the hook to move the same into position over the rungs of the stationary section is effected by a trip which yields only upwardly, said trip being pivoted to said hook above the pivotal point of the latter, and having a cam surface that engages the lower face of the rungs of the stationary ladder to effect the movement of said hook. By this means, when the trip engages the under face of a rung on the lower section, the 45 hook is positively moved to a position immediately over the next lower rung, and when the hook engages the under face of a rung on the lower section, the trip is positively moved to a position immediately 50 below the next higher rung. Further, when it is desired to lower the upper section, said trip readily yields as it engages the upper face of each of the rungs of the lower section that it passes.

The invention will be better understood 55 by reference to the accompanying drawing, illustrating one expression of the inventive idea, and wherein—

Figure 1 is a perspective view showing the lower ends of a stationary and movable 60 section, the upper part of each of these sections being broken away; Fig. 2 is an enlarged vertical section on the line 2—2 of Fig. 1, looking in the direction of the arrows; Fig. 3 is a transverse section on the 65 line 3—3 of Fig. 2, looking in the direction of the arrows; and Fig. 4 is a view showing the several parts of the improved device pulled out or separated to better illustrate 70 their construction and the way they are assembled and disassembled.

Referring to the drawings, wherein like reference characters indicate like parts, A indicates generally the lower ladder or section, B the upper ladder or section, and C 75 the combined side guard or guide and hook member for securing the sections in extended position. It is to be understood that more than two sections may be employed and that, while a single device C may be used to 80 connect two sections, two such devices are preferably employed, one being secured to each side rail of the section B. Inasmuch, however, as the construction and operation of each are identical, it will only be necessary to describe one.

Referring particularly to Figs. 3 and 4, 5 indicates a side guard or guide that is suitably secured to the side rail 6 of the upper or movable ladder section. This guard or 90 guide is preferably provided with substantially parallel members 7 and 8 that engage opposite faces of said side rail 6, said members being connected by an integral part 9 that engages the edge of said side rail 6. 95 The member 8 is provided with a perforated stud or projection 10, preferably formed integrally therewith, and in the preferred embodiment of the inventive idea said guard or guide is secured to the side rail 6 by a bolt 100 11 that passes through members 7 and 8, side rail 6 and stud 10. Preferably, too, additional securing means are provided in the form of screws passing through holes 12 and 13 (Fig. 4) in part 9. The guard or 105 14 is provided with a part that engages the outer face of one of the side rails 14 of the lower or stationary ladder section, and

with parts 15 and 16 that engage the edges of said side rail 14.

In devices of this character, a hook member is usually employed to maintain the sections in extended position, said member being moved by suitable means into engagement with the desired rung of the lower or stationary section.

As herein shown, 17 indicates the improved hook member that is employed, said member, according to the present invention, being pivotally mounted on the side guard 5, the stud 10 snugly engaging in an opening 18 in said member. It has been experienced that, by mounting the hook member on the side guard, there is secured a device of great strength, simplicity, and compactness, thus largely reducing the danger of breakage and accident. Preferably, a cover 20 or casing is employed to protect the parts and, as here shown, said casing consists of a face plate 19 (Fig. 4) and a part 20 which latter is provided with a cut-out portion 21 in which the member 8 of the guard or guide fits. Said part 20 is also provided with projections 22 and 23 that engage one edge of the side rail 6, this construction insuring a close fit of the cover to the other parts. Further, said cover is provided, preferably integrally, with a rib or ridge 24 against which bears a spring 25, one end of which is secured to the part 20 at 26. The function of this spring is to positively hold the hook member 17 in either of the two positions to which it may have been shifted. When the hook member has been shifted into position to engage a rung on the lower or stationary section (Fig. 2), the free end of said spring will engage a cam face 27 (Fig. 4) provided near the pivot of said hook and will hold the hook positively in that position; whereas, when the parts are shifted to the full line position shown in Fig. 2, the spring will engage a cam face 28 to hold the parts in said full line position.

As will be observed, the present device is so constructed and applied to the upper or movable section that it is unnecessary to remove a rung from said section to mount the device thereon, which removal would weaken the section; and, further, when the upper and lower sections are secured in extended position by the improved device, the rungs on the two sections are opposite one another.

The hook 17 is automatically shifted into position to engage the desired rung on the lower section by means of a positively acting trip 29 that is pivoted at 30 to a bifurcated projection 31, preferably formed integrally with said hook 17. This trip is enlarged or weighted at 32, so that when the parts are in the full line position shown in Fig. 2, said trip will always be immediately below the next higher rung on the lower or

stationary section. Further, said trip is provided with an inclined or cam surface 33, and when the upper or movable section is being raised, the engagement of this cam surface with the lower face of the next higher rung—34 (Fig. 2) for example,—effects the positive movement of the parts from the full to the dotted line position shown in Fig. 2. When the trip is in the full line position indicated, a shoulder 35 engages a face 36 of the projection 31, so that said trip can only move upwardly when it engages the rungs of the lower or stationary section and, when the movable section is being elevated, this engagement of shoulder 35 and face 36 causes the trip and hook to move positively as a unit when the former engages the under faces of the rungs of the lower section.

The operation of the device is as follows: When the parts are assembled in position, the upper and lower sections will be held together during relative movement by the side guard or guide with the parts in the position shown in full lines in Fig. 2. If it is desired to engage the projection 37 of the hook 17 with the rung 38 of the stationary section, the movable section of the ladder is elevated in any suitable manner, thus engaging the cam surface 33 with the lower face of the rung 34 which causes the hook to be swung around its pivot toward the right, (as shown in Fig. 2) against the tension of spring 25. The hook will thus assume a position immediately above that shown in dotted lines and, if the upper section is then lowered, the parts will be moved to the dotted line position, with the projection 37 in engagement with the rung 38. The parts are held positively in this position by the engagement of spring 25 with cam face 27. It will be observed that, in the dotted line position, the trip 29 is out of line with the rungs of the stationary section. To lower the movable section, it is first elevated until the surface 39 of the hook 17 engages rung 34, which causes said hook to swing around its pivot, thus moving projection 37 to the left out of line with the rungs on the stationary section, and at the same time moving trip 29 to the right in line with said rungs. The engagement of spring 25 with cam surface 28 holds the parts positively in this position. In view of the fact that the trip 29 is free to move upwardly around its pivot 30, as the upper section is lowered, said trip will yield as it engages each rung of the lower section and, in such lowering operation, said trip is the only part moving with the hook 17 that contacts with the rungs of the lower section. It will thus be understood that, in elevating the movable section, the engagement of the trip with succeeding rungs of the stationary section forces the hook into position to engage said

rungs, whereas the engagement of surface 39 forces the hook out of line with the rungs of the stationary section and the trip into line therewith—the cam surface 33 and surface 39 alternately engaging the under face of each succeeding rung of the lower section as the upper section is raised.

It is pointed out that the improved device is so constructed that it may be assembled 10 either on the right or left-hand side of a ladder section, without change of any kind.

While one expression of the inventive idea has been herein described in detail, it is to be understood that the inventive idea is not 15 limited to the structure illustrated but may receive various mechanical expressions conforming to the definition of the invention contained in the following claims.

What is claimed is:—

20 1. In an extension ladder comprising movable and stationary sections, the combination of a side guard or guide carried by the movable section, a hook member mounted on said side guard, means automatically moving said member into position to engage the rungs of the stationary section, and a bolt passing through said side guard and hook member.

25 2. In an extension ladder comprising upper and lower sections, the combination of a side guard mounted on and engaging the side of the upper section at diametrically opposite points, a hook member mounted on said guard and automatically engaging the rungs on the lower section, and a bolt passing through said side guard at two points and through said hook member.

30 3. In an extension ladder comprising upper and lower sections, the combination 40 of a side guard mounted on and engaging opposite faces of the side of the upper section, a hook member mounted on said guard and automatically engaging the rungs on the lower section, and a bolt passing through said side guard at two points and through said hook member.

35 4. In an extension ladder comprising upper and lower sections, the combination 50 of a side guard mounted on one side of the upper section and having a stud or projection thereon, a hook member mounted on said projection, and means securing said side guard and member in place.

45 5. In an extension ladder comprising upper and lower sections, the combination 55 of a side guard mounted on one side of the upper section and having a stud or projection thereon, a hook member mounted on said projection, and a bolt passing through the side of said ladder and said projection.

60 6. In an extension ladder comprising upper and lower sections, the combination of a side guard mounted on one side of the upper section and having a stud or projection thereon, a hook member mounted on

said projection, a bolt passing through the side of said ladder and said projection, and a cover mounted on said bolt.

65 7. In an extension ladder comprising upper and lower sections, the combination of 70 a side guard having parallel members engaging opposite faces of one side of the upper section and an extension engaging the lower section, a hook member mounted on said side guard, and a bolt passing through said 75 parallel members, the side of the upper section and said hook member.

8. In an extension ladder comprising upper and lower sections, the combination of a 80 side guard having parallel members engaging opposite faces of one side of the upper section and an extension engaging the lower section, a hook member mounted on said side guard, a bolt passing through said parallel members, the side of the upper section and 85 said hook member, and a cover mounted on said bolt.

9. In an extension ladder comprising upper and lower sections, the combination of 90 a side guard having parallel members engaging opposite faces of one side of the upper section and an extension engaging the lower section, a projection formed on one of said members, a hook member mounted on said projection, and a bolt passing 95 through said side of the upper section and said projection.

10. In an extension ladder comprising upper and lower sections, the combination 100 of a side guard having parallel members engaging opposite faces of one side of the upper section and an extension engaging the lower section, a projection formed on one of said members, a hook member mounted on said projection, a bolt passing 105 through said side of the upper section and said projection, and a cover mounted on said bolt.

11. In an extension ladder comprising upper and lower sections, the combination 110 of a pivoted hook member on the upper section, a trip pivotally mounted on said hook member above the pivot point of the latter, said trip having an inclined face that engages the lower face of the rungs on the 115 lower section to positively move said member over a rung below that engaged by said trip.

12. In an extension ladder comprising upper and lower sections, the combination of 120 a pivoted hook member on the upper section, a trip pivotally mounted on said hook member above the pivot point of the latter and moving only upwardly, said trip having an inclined face that engages the lower face 125 of the rungs on the lower section to positively move said member over a rung below that engaged by said trip.

13. In an extension ladder comprising upper and lower sections, the combination 130

of a pivoted hook member on the upper section, a weighted trip pivotally mounted on said hook member above the pivot point of the latter, said trip having an inclined face that engages the lower face of the rungs on the lower section to positively move said member over a rung below that engaged by said trip.

In testimony whereof I have signed this specification in the presence of two subscr- 10
ing witnesses.

CHARLES R. CONABEE.
